DESIGN FOR A SPOON OR SIMILAR ARTICLE

Carl C. Braun, New York, N. Y., assignor to Reed & Barton, Taunton, Mass., a corporation of Massachusetts

Application February 10, 1936, Serial No. 61,073

Term of patent 14 years

To all whom it may concern:

Be it known that I, Carl C. Braun, a citizen of the United States, residing at 186 East End Avenue, New York city, in the county of New York and State of New York, have invented a new, original, and ornamental Design for a Spoon or Similar Article, of which the following is a specification, reference being had to the accompanying drawing, forming a part hereof.

Fig. 1 is a front elevational view of a spoon showing my new design;

Fig. 2 is a rear elevational view; and Figs. 3, 4, 5, and 6 are sectional views taken on the lines 3—3, 4—4, 5—5, and 6—6 respectively, on Figs. 1 and 2.

I claim:

The ornamental design for a spoon or similar article as shown.

CARL C. BRAUN.
